UNITED STATES PATENT OFFICE.

ALBERT M. BULLARD, OF NEW YORK, N. Y., ASSIGNOR TO WESTERN ELECTRIC COMPANY, OF CHICAGO, ILLINOIS, A CORPORATION OF ILLINOIS.

ALARM AND CURRENT-SAVING APPARATUS FOR AUTOMATIC EXCHANGES.

949,881.

Specification of Letters Patent. Patented Feb. 22, 1910.

Application filed February 6, 1908. Serial No. 414,498.

To all whom it may concern:

Be it known that I, ALBERT M. BULLARD, citizen of the United States, residing at New York, in the county of New York and State of New York, have invented a certain new and useful Improvement in Alarm and Current-Saving Apparatus for Automatic Exchanges, of which the following is a full, clear, concise, and exact description.

10 My invention relates to automatic telephone exchange systems, and its object is to provide improved means for calling attention to an abnormal condition, such as an accidental ground connection which may 15 exist on any line of the exchange, and to prevent the waste of current which would otherwise result from the existence of such ground connection.

The invention is applicable more especially to automatic exchanges such as that described in Patent No. 826,310 granted to me July 17th, 1906, having so few lines that it would not be economical to keep a repair man at the place or town where the system 25 is installed. It is possible to so design a system of this description that the apparatus and the central battery will seldom need personal attention. The lines, however, particularly when they are of overhead construction, are liable to become grounded in various ways, and if the battery side of a line becomes grounded, a very appreciable portion of the energy of the battery may be wasted before the trouble is discovered and 30 corrected. The loss of current is considerably greater in an automatic exchange than it is in a manual exchange because the selecting mechanisms in the local circuits of the line relays require a comparatively heavy 35 current for their operation,—much greater than that which would flow in any line circuit, however short.

In accordance with the present invention, I provide in the local circuit of the line relay 45 of each line a protective device which in response to an abnormal flow of current will cause the supply of current to both the line circuit and local circuit of the affected line to be cut off, thus stopping the waste of current, and will also cause a signal to be given 50 at some point where there are persons in attendance, as at a neighboring manual exchange, so that the difficulty may be discovered and corrected without delay. I also 55 preferably provide means whereby, if the

trunk line leading to the manual exchange is busy at the time the trouble occurs, the signal will be postponed or stored up, so to speak, and made manifest only when the trunk line becomes free.

60

I will describe my invention more particularly by reference to the accompanying drawing, which is a diagram illustrating the circuits and apparatus of one of the lines of an automatic telephone exchange including a trunk line extending from such automatic exchange to a distant manual exchange; an operator's cord circuit at the manual exchange being also shown.

65

The circuits and apparatus of the automatic exchange system shown in the drawings are in general the same as those shown in Figure 1 of my prior patent above referred to with the addition of certain apparatus and circuits hereinafter described, 70 for the purpose of accomplishing the results above outlined. The same reference characters and letters which are used in Fig. 1 of my said prior patent are also applied to corresponding parts in the drawing of the 75 present application, and the general characteristics and mode of operation of the automatic exchange will be apparent by reference to that patent. In the system shown, the selecting mechanism associated with 80 each line of the automatic exchange is operated by stepping and holding magnets which are connected in a local circuit 5, 6, 8 controlled by the line relay *c*. In the selecting operation this local circuit is intended to be 85 opened and closed very rapidly and not to remain continuously closed for any considerable period of time. It is true that the local circuit for the holding magnet is kept 90 closed during conversation after the selecting operation has been completed, but at that time the high resistance relay *k* is included in the local circuit so that an excessive 95 flow of current does not then occur. Normally, however, the relay *k* is short-circuited by the branch 8 controlled at the back 100 contact of the line relay *a*. It is evident that in the system shown if an accidental ground connection should exist on the battery side 2 of the subscriber's line, as at the point marked 50, the line relay *c* would be 105 continuously excited and there would be an opportunity for serious waste of current in the local circuit 5, 6, 8 except for the provision hereinafter to be described.

110

In applying the present invention to the system shown, a device is provided in the local circuit 5, 6, 8 of each line, adapted to respond to a continuous flow of current such as would result if the line relay *c* should remain continuously excited; and this device in its response is adapted to bring about the opening of the circuit or circuits in which the current is wastefully flowing, and will 5 also bring about the giving of the alarm signal. The responsive device may be of any suitable kind, but as the time of application of current should be a necessary factor in its operation, in order that it may not respond to the ordinary intermittent selecting impulses, I prefer to use a "heat coil" of the ordinary type. Such a device comprises a coil of wire wound upon a spool in which a pin 53 is held under tension by easily-fusible solder. The pin normally holds a spring 52 away from a contact anvil or plate 27, but when released permits these parts to come together and close an electric circuit. As shown, the circuit 29 is adapted to be 10 closed by the contact device of the heat-coil 26. This circuit includes a low-resistance winding of a relay 30, and a fuse 25 is also provided in this circuit which is adapted to be blown when the circuit is closed through 15 said low resistance relay winding; the blowing of the fuse serving to disconnect the central battery from the line and local circuits of the affected line. The current will flow long enough however to cause relay 30 to attract its armature, which controls a locking circuit including a high resistance winding 31 for said relay. This locking circuit has two branches, one through a back 20 contact of a signal-controlling relay 32 and through a resistance 33 to earth, and the other through the winding of said relay 32 through conductor 34, back contact 35 of relay *k*³⁷, wire 36, and back contact 37 of line relay *c*³⁴ of the trunk line to earth. The 25 relays which are directly associated with the trunk line are the ordinary relays such as are provided for each line of the automatic exchange, the only special relays required for the present invention being relays 30 and 32, which are not individual to any line but serve for the whole exchange.

The alarm signal to be given upon the response of relay 32 is preferably the mere display of the line signal associated with the trunk line at the manual exchange coupled with the application of the ordinary "busy-buzz" current to the trunk line, to warn the operator of the trouble when she makes connection with the trunk line in answer to the signal. It is evident however that the alarm or signal to be given in response to the operation of the protecting device 26 of any line may be of any desired character, whether visual or audible, or both, and at 30 any desired place.

Relay 32 is adapted when excited to apply ringing current from the grounded generator *G* through lamp 39 and contact 40 to the line wire 41 of the trunk line from which the annunciator drop or line signal 49 is normally connected in a branch to ground from the springjack at the manual exchange. Relay 32 is also arranged to close a contact 44 governing a circuit 45 through the winding *t*²² of the busy-test and lockout relay *t*³⁸ 70 associated with the trunk line. This lockout relay when excited closes a contact 46 controlling a locking circuit through its own winding, and also closes a contact 43 which applies busy-buzz current from induction coil *u* to the line wire 42 of the trunk line. 75 It will be understood that the heat coils or other responsive devices 26 for each line are not the usual heat coils which in practice are included in the line circuit, but are 80 special devices located in a local circuit. Each line may of course be provided with the ordinary protective devices such as lightning arresters, heat coils, or "sneak-current arresters" and fuses, in addition to 85 the special equipment herein disclosed. While several batteries each marked *b* are illustrated in the drawing for the sake of simplicity in showing circuit connections, these batteries in practice may be and 90 preferably are one and the same. 95

The operation of the alarm and current-saving equipment is as follows: If the battery side 2 of any line becomes grounded, accidentally or otherwise, the relay *c* of such line is immediately excited and closes contact 28. This completes a local circuit from the central battery *b* through the line fuse 25, contact 28 of line relay *c*, conductor 5, heat coil 26, normal contact of test relay *t*, 100 conductor 6, holding magnet *d* and stepping magnet *e* of the selector, and thence by conductor 8 through a back contact of relay *k* and back contact of relay *a* to earth. The operating magnets *d* and *e* of the selector 105 are of low resistance, and the volume of current going through the heat-coil 26 will cause the operation of said heat-coil in about one minute provided the ground is not removed from the line. When the heat-coil 110 operates, the spring 52 closes against its front contact plate 27 and thereby completes a circuit from conductor 5 through conductor 29 and the low resistance winding of 115 relay 30 to earth. The closure of this low resistance circuit 5, 29 causes the line fuse 25 to be blown, thereby disconnecting the central battery *b* from the subscriber's line and local circuit, thus preventing further waste of current. Relay 30, in drawing up 120 its armature, closes a circuit from battery *b* through the high resistance locking winding 31 of said relay, through a back contact of relay 32 and resistance 33 to earth. The resistance is introduced to reduce the amount 125 130

of current flowing in this circuit and also to permit the subsequent operation of relay 32 which, if the resistance 33 were omitted, would be short-circuited.

- 5 Assuming that the trunk line is not in use at the time when the accident occurs, relay 32 will be immediately operated over a circuit in multiple with a resistance 33 which may be traced through the winding of relay 10 32 to conductor 34, through back contact 35 of relay h^{37} of the trunk line, thence over conductor 36 and through the normal contact 37 of the line relay c^{54} of the trunk line to earth. Relay 32, in attracting its armature, disconnects the branch containing the 15 resistance 33 and leaves the circuit for relay 30 dependent upon the continuity of the other branch controlled by relays h^{37} and c^{54} , as previously traced. Relay 32 also by closing contact 40 applies current from the ringing generator G through the resistance lamp 39 to line wire 41 of the trunk line and so to the annunciator 49 at the distant manual exchange, thus displaying the line signal to 20 the operator. The signal-controlling relay 32 also by closing contact 44 applies current from battery b in a circuit through conductor 45 and winding t^{22} of the test relay t^{38} to earth. When the operator at the manual 25 exchange answers the signal given by the falling of the annunciator drop, the insertion of her answering plug closes a metallic circuit over the trunk line which causes the relays c^{54} and a^{55} to be operated. When relay 30 30 c^{54} breaks the contact 37 it also makes a contact 48 by which current is applied from the central battery b through the fuse 25 of the trunk line, contact 48, heat-coil 47, front contact 46 of relay t^{38} through the winding t^{22} 35 of said relay to earth. Relay t^{38} thereby remains excited. The heat coil 47 associated with the trunk line is not operated at this time because of the high resistance of winding t^{22} . The relay t^{38} by maintaining contact 43 closed applies busy-buzz current from the induction coil u , over conductor 12 through condenser m to the line wire 42 of the trunk line and thence through the operator's telephone apparatus at the manual 40 exchange and back over line wire 41 and through relay a^{55} to earth. Relays 30 and 32 are now released by the opening of contact 37 of the line relay c^{54} , the further excitation of these relays 30 and 32 being unnecessary. 45 The operator upon hearing the busy signal immediately following the display of the line signal of the trunk line will know the nature of the trouble at the automatic exchange and will see that a repair man is sent to investigate and correct the difficulty. In small exchanges to which this invention is applicable there will be so few lines that it is obviously unnecessary for the number of the line in trouble to be transmitted to the 50 distant operator, as a glance at the battery 45

fuse panel at the automatic exchange will tell which fuse has been blown. When the operator withdraws her answering plug from the spring jack of the trunk line the relays c^{54} and a^{55} will be released. The relay 70 c^{54} will in turn release the relay t^{38} . The entire apparatus of the trunk line is now restored to normal condition so that the trunk line will be available for its legitimate use. 75

If a trunk line is in use when the subscriber's line of the automatic exchange becomes grounded, the notification to the operator at the manual exchange will be deferred until the trunk line is free. During 80 the use of the trunk line the circuit for relay 32 is broken at the contact 37 of line relay c^{54} of the trunk line, but relay 30 remains excited by current flowing through its winding 31 and through the back contact of 85 relay 32 and resistance 33 to earth. If at the time the trouble occurs the line relay c^{54} of the trunk line is being rapidly operated to open and close its contacts, as in the process of selection, the relay 32 will not 90 respond, because it is made slightly sluggish in its operation by the provision of a copper jacket upon its core. As soon as the trunk line is free, however, the relays c^{54} and h^{37} are restored to normal condition, 95 whereby the circuit is completed for relay 32 and the notification given to the operator at the manual exchange as before described. 100

If the trunk line for transmitting the signal to the manual exchange operator should 105 become grounded on its battery side 42, the heat coil 47 of the trunk line will be operated, and will blow the fuse and cause the operation of the relay 30 as before described in connection with an ordinary subscriber's 110 line. The line signal 49 will be displayed before the operator and the busy tone will also be heard except in the extremely rare case of a ground connection of practically zero resistance at a short distance from the exchange. Furthermore, the operator will find the trunk line dead because the fuse 25 has been blown. Relay t^{38} will be maintained excited by current flowing in its winding t^{22} until the inspector clears the 115 trouble. Relays 30 and 32 will also remain operated until then.

It will be observed that the heat coil or similar responsive device is placed not in the line circuit but in the local circuit controlled by the line relay. One of the principal advantages of this arrangement is that the current variations between minimum and maximum in the local circuit are relatively small as compared with the current 120 variations in the line circuit. The variations in the local circuit are caused only by variations in the electromotive force of the central battery, which in a well-designed exchange are small. The variations in the 125

line circuit result not only from variations in the electromotive force of the battery, but also from variations in line resistance, and shunts upon the line due to accidental 5 grounds.

I claim:—

1. In a telephone exchange, the combination with a source of current, and a line circuit connected therewith, of switching mechanism responsive to current in said line circuit and adapted for rapid intermittent operation, a device responsive to a continued flow of current in said line circuit, but not responsive to rapidly-changing current, and 10 means controlled by said responsive device for cutting off the supply of current.

2. In a telephone exchange, the combination with a source of current, and a line circuit connected therewith, of a relay in the 15 line, a circuit controlled by said relay, switching mechanism in said circuit adapted for rapid intermittent operation, a device in said circuit responsive to a continued flow of current, but not responsive to rapidly-interrupted current, and means controlled by said responsive device for cutting off the supply of current.

3. The combination with an automatic telephone exchange having line relays in the 20 subscribers' lines and selecting mechanism in local circuits of said line relays, of a responsive device in the local circuit of a subscriber's line relay, said device being adapted for actuation only by a long-continued 25 flow of current, and a signal controlled by said responsive device.

4. The combination with an automatic telephone exchange, a manual exchange and a trunk line connecting them, of a protective 30 device 26 associated with a line of the automatic exchange, and means controlled by said protective device for applying current to the trunk line.

5. The combination with an automatic 35 telephone exchange, a manual exchange and a trunk line uniting them, of a signal associated with the trunk line at the manual exchange, a protective device associated with a line of the automatic exchange adapted to 50 respond to an abnormal flow of current, and means controlled by said protective device for causing the operation of said signal.

6. The combination with an automatic telephone exchange, a manual exchange and a trunk line uniting them, of a line signal 55 associated with the trunk line at the manual exchange, a protective device associated with a line of the automatic exchange, adapted to respond to an abnormal flow of current, and means controlled by said protective device for causing the display of said line signal, and means also controlled by said protective device for applying a tone-producing current to the trunk line.

65 7. The combination with an automatic

telephone exchange, a manual exchange and a trunk line uniting them, of a protective device associated with a line of the automatic exchange adapted to respond to an abnormal flow of current, a signal associated with the trunk line, means for operating said signal, and a relay associated with the trunk line arranged to bring said signal-operating means under control of said protective device, during the idle condition of 75 said trunk line.

8. The combination with a telephone line 41, 42, of a signal-controlling device 32, a protective device responsive to an abnormal flow of current, a line relay and means for 80 exciting the same during the use of said telephone line, a circuit for said signal controlling device controlled at a back contact of said line relay, and means controlled by said protective device for applying current 85 to said circuit of said signal-controlling device, whereby upon the operation of the protective device the signal is not given until said telephone line is free.

9. The combination with an automatic 90 telephone exchange system, a manual exchange and a trunk line uniting them, of a protective device associated with a line of the automatic exchange, a signal controlling device 32, a relay c^{54} excited during the use 95 of the trunk line, a circuit for said signal-controlling device, controlled at a back contact of said relay c^{54} , and means controlled by said protective device for applying current to said last-mentioned circuit. 100

10. The combination with an automatic telephone exchange, a manual exchange and a trunk line uniting them, a protective device associated with a line of the manual exchange, a relay 32, means controlled thereby 105 for applying signal current to the trunk line, a line relay for the trunk line excited during the use thereof, a circuit for said relay 32 controlled at a back contact of said line relay, a relay 30 adapted to apply current to said relay 32 and having a locking winding in a circuit controlled at a back contact of said relay 32, and an energizing circuit for said relay 30 adapted to be closed by said protective device. 110

11. In a telephone exchange system, the combination with a source of current and a line circuit connected therewith, of switching mechanism responsive to current of one character in said line, a device responsive 120 only to current of another character in said line, and means controlled by said responsive device for cutting off the supply of current. 115

In witness whereof, I hereunto subscribe my name this 30th day of January A. D., 125 1908.

ALBERT M. BULLARD.
